CLAIM

An ornamental design for a footwear article, as shown and described.

DESCRIPTION

FIG. 1 is a front side view of a footwear article—according to the present invention.

FIG. 2 is a rear side view of the footwear article of FIG. 1.

FIG. 3 is a right view of the footwear article of FIG. 1.

FIG. 4 is a left perspective view of the footwear article of FIG. 1; and,

FIG. 5 is a top view of the footwear article of FIG. 1.

The bottom of the footwear article forms no part of the claimed design.
